Primary Examiner — Kimberly Barnes

(57) CLAIM

The ornamental design for a main unit for vacuum cleaner, as shown and described.

DESCRIPTION

1. Main unit for vacuum cleaner
- 1.1: Front view of main unit for vacuum cleaner showing the claimed design
- 1.2: Back view thereof
- 1.3: Left view thereof
- 1.4: Right view thereof
- 1.5: Top view thereof
- 1.6: Bottom view thereof
- 1.7: First Perspective view thereof
- 1.8: Second Perspective view thereof

The portions of the main unit for vacuum cleaner shown in broken lines form no part of the claimed design.
